UNITED STATES PATENT OFFICE.

JOSEPH NEEDHAM, OF HANDSWORTH, COUNTY OF STAFFORD, ASSIGNOR TO
WILLIAM WELLINGTON GREENER, OF BIRMINGHAM, ENGLAND.

BREECH-LOADING FIRE-ARM.

SPECIFICATION forming part of Letters Patent No. 248,339, dated October 18, 1881.

Application filed August 6, 1881. (No model.) Patented in England April 7, 1874.

To all whom it may concern:

Be it known that I, JOSEPH NEEDHAM, of Handsworth, in the county of Stafford, England, have invented certain Improvements in Breech-Loading Fire-Arms, of which the following is a specification.

My invention relates to that class of fire-arms known as "drop-down" guns; and the invention consists, first, in so constructing the extractors of a double gun that either one may be operated independently of the other; second, in so connecting the extractors with the lock that the latter shall act upon the former in such a manner as to eject the spent shell from the barrel; and, third, in means for rendering the gun more safe when cocked, all as hereinafter more fully described.

Figure 1 is a longitudinal section, showing the breech closed and the gun cocked. Fig. 2 is a similar view, showing the parts in the position they occupy when the breech is open and the shell ejected. Fig. 3 is a rear-end view of the barrels, with their extractors and ejector-levers; and Fig. 4 is a side elevation of the tumbler and sear, shown detached.

This invention is applicable alike to both single and double guns, but in the drawings I have represented the invention as applied to a double gun, inasmuch as that is the style of gun on which it will generally be used, and which will best serve to illustrate my invention. In the first place, the extractors C, instead of being made of a single plate, so as to withdraw the shells from both barrels at once, are made of two separate plates, as shown in Fig. 3, each having a separate stem, e, and a separate guide-pin, a, the two stems e being made flat on their adjoining faces, so as to fit side by side in the same hole. On their under faces these stems e are cut away or flattened, as shown in Figs. 1 and 2, and a screw, b, is inserted so that its point will rest in the recess thus formed, thereby serving as a stop to limit their outward movement.

In the rear end of the lump underneath the barrels I form a central recess in which I pivot two levers, l, they being arranged side by side on the pivot n, as shown in Figs. 1 and 2, and which I term the "ejectors." These levers have

5 their upper ends resting against the forward face of the extractors C, as shown in Fig. 1, each lever bearing against its corresponding extractor, so that either may operate independently of the other. As shown in Figs. 1 and 2, these ejectors or levers l have their lower ends provided with a short arm which projects backward nearly at a right angle from the body of the lever, upon which the arm of the lock operates to eject the shell, as herein-after explained. The hammer or tumbler H 60 in this case is shown as being arranged internally with a firing-pin or striker, v, pivoted to its upper end and arranged so that its point will strike at the center of the head of the shell. As shown, this firing-pin v has a shoulder near 65 its front end, and a small bolt cut away on one side, so as to form an eccentric, is mounted in a transverse hole in such a position that when turned in one position it will engage with the shoulder of the firing-pin or striker, and thus 70 act as a guard or safety attachment to prevent the gun from being discharged accidentally, there being a small arm or lever attached to this stop g on the outside of the lock-plate, as shown in dotted lines, by which it can be turned 75 at will in either direction.

To the tumbler or its axis T an arm, m, is rigidly secured, as shown in Figs. 1 and 2, its front end projecting forward through a recess far enough to rest upon the rearwardly-projecting arm of the ejector-lever l, as represented in Fig. 2.

A small projection, o, is formed on the rear face of the lump, nearly opposite the pivot of the levers l, as shown in Figs. 1 and 2, which projection o, as the breech is opened by dropping the barrels, comes in contact with the arm m and raises it until the projection o, moving in the arc of a circle, slips from under the end of arm m, which, being impelled by the main-spring, is suddenly thrown down until it strikes upon the arm of the lever l, to which it imparts a sudden movement, and which in turn acts with equal force and suddenness upon the extractor C, thereby causing the latter to eject 95 the shell entirely from the barrel, as represented in Fig. 2.

As the arm m of the lock, after having struck the lever l, as above described, will still rest upon it, it follows that as the barrels continue 100

their dropping movement the arm *m* is raised far enough to permit the nose or point of the sear to enter the "bent" or notch of the tumbler, whereby the arm is cocked in the act of dropping the barrels, so that the dropping of the barrels, it will be seen, has the twofold effect of ejecting the shells and cocking the gun, the two acts taking place almost simultaneously. From the fact that the arm *m* of the lock that has not been released will still remain raised to the position shown in Fig. 1, and can only strike the lever *l* when the arm has been let down by pulling the trigger of that lock, it follows that only that shell which has been exploded (or struck by the firing-pin in case it does not explode) will be ejected or thrown out of the barrel, the unexploded or unstruck shell being simply drawn outward or retracted for a short distance in consequence of the lower arm of lever *l* coming gradually in contact with the breech-piece or of the arm *m*, which will cause the lever *l* to turn gradually on its pivot and impart to its extractor a corresponding movement. It will therefore be seen that if both barrels have been fired the dropping of the barrels will eject both shells and cock both locks; but if only one barrel has been fired then the dropping of the barrels will eject the spent shell, retract the live shell, and at the same time recock the lock that was released.

While I have thus shown a very simple means of connecting the locks with the extractors by means of the arms *m* and the levers *l*, it is obvious that they may be connected by other means, or devices, and still be made to produce the same result; and hence I do not confine myself to these special devices or means, as this feature or part of my invention consists, broadly, in so connecting the locks with the extractors that the dropping of the barrels shall cause the mainspring of the lock or locks to act as the motor for ejecting the shell or shells.

It is obvious that the hammers may be arranged externally, if desired, and that, instead of the arms *m*, links may be used.

It is also obvious that instead of arranging the operating devices internally, they may be arranged externally; but I prefer to locate them internally, as shown.

The third feature of my invention is shown in Figs. 1; 2, and 4, but more distinctly in the latter. As there shown, each sear *S* is provided with a projection, *t*, which is so located that it will be pressed against by the hammer or tumbler *H* as the latter is forced back in the act of cocking the arm, and which thus acts to force the nose or point of the sear into the "bent" or notch of the tumbler to its full depth, thus causing the sear to take a firm hold on the tumbler, and thereby rendering the arm more safe. A spring, *y*, is applied to the sear, as shown in the drawings, or in any suitable manner. This feature of my invention is applicable to all gun-locks in which a tumbler and sear are used, but is more especially val-

able in guns like this, in which the hammers are located internally, where they cannot be seen, and which are therefore termed "hammerless" guns.

It is obvious that the locks may be arranged to be cocked by hand and still be made to operate upon the extractors so as to eject the shells, which is the main feature of my present invention.

By constructing a gun on this plan the dropping of the barrels ejects the spent shell or shells, and at the same time cocks the arm and renders it more safe. The locating of the hammers internally also prevents those accidents which are so frequently caused by the external hammers being struck or caught against objects, such as the limbs of trees, the sides or seats of boats or other vehicles, fences, and the like; but this feature, as also that of cocking the arm by the dropping of the barrels, I do not claim as my invention, they having been previously used by others, but not in the manner here shown.

At the rear end of the lump is formed a tongue or projection, *J*, upon which a pivoted latch, *I*, engages to lock the barrels down, the latch *I* being moved by the hand-lever *L*, located under the guard, as shown in Figs. 1 and 2.

I am aware that arms have been patented in which the hammer was cocked by the dropping of the barrel, and also that a gun has been patented in which three barrels are shown, with one double and one single extractor, all operated together; but said devices are not adapted for use in a gun such as I have described, and I do not claim them as my invention; but

What I do claim is—

1. In combination with a double-barreled drop-down gun, the double extractors *C C*, both being arranged side by side, and having their stems *a* both fitted in the same hole, substantially as and for the purpose set forth.

2. In combination with a pivoted or drop-down barrel, *B*, the extractor *C*, ejector-lever *l*, and a lock provided with a projection, *m*, or equivalent means for operating said lever for the purpose of ejecting the spent shell, substantially as set forth.

3. In combination with a drop-down barrel, the lever *l*, pivoted to and being carried by said barrel, and arranged to engage with an arm or projection on the tumbler of the lock for the purpose of automatically cocking the arm, as set forth.

4. The combination, in a drop-down gun, of the extractor *C*, projection *o*, lever *l*, and arm *m*, connected to the lock, all being arranged to operate substantially as described, whereby the dropping of the barrel is made to automatically eject the spent shell and cock the arm.

JOSEPH NEEDHAM.
